RANGE CONTROL SWITCH

Application filed October 22, 1926. Serial No. 143,411.

My invention relates to circuit-controlling devices and more particularly to small switches used in connection with household appliances.

5 One object of my invention is to provide a switch that shall be set in one position preparatory to being moved through a series of positions.

Another object of my invention is to provide 10 a switch that shall be set in one position and biased to another position by automatically controlled operating means.

Another object of my invention is to provide 15 a switch that shall be set in one position and subsequently moved through a series of positions upon the actuation of a single electromagnet.

Another object of my invention is to provide 20 a switch, the electrical position of which shall be readily distinguishable by observation.

A further object of my invention is to provide 25 a switch that shall be particularly useful in connection with electrical appliances wherein it is desired to employ a switch to automatically perform a plurality of operations.

In the operation of an electrical appliance, particularly an electric range, it is often 30 found desirable to set the main control switch in such position that a circuit through the appliance may be closed at a desired hour and remain closed for a predetermined time. In connection with an electrical range this advantage is particularly pronounced when a 35 clock is set to heat the oven at a given hour and the current through the oven is interrupted when the oven has reached a given temperature, all of these operations being 40 automatically performed after the setting of the clock and the control switch.

Heretofore, it has been the general practice 45 to employ snap switches in connection with electrical ranges that necessitated the operator walking to the switch to determine whether it is in its "on" or "off" position.

In the present invention, I provide a switch 50 with an operating handle, the position of which readily indicates the "on" or "off" position of the switch. The position of the op-

erating handle may be observed in all the operating positions of the switch.

My invention relates to the switch for accomplishing the foregoing objects and to the details of construction illustrated in the accompanying drawings wherein:—

Figure 1 is a side elevational view of a switch embodying my invention in its "off" position.

Fig. 2 is a front elevational view of the 60 switch shown in Fig. 1.

Fig. 3 is a view similar to Fig. 1, showing the switch in its set position.

Fig. 4 is a view similar to Fig. 3 showing the 65 switch in its "on" position.

Figs. 5 and 6 are detail side elevational and edge views, respectively, of the switch arm.

Figs. 7 and 8 are similar views, of the 70 switch arm trigger.

Figs. 9 and 10 are similar views of the 75 operating handle trigger, and

Figs. 11 and 12 are similar views of the 80 operating handle.

My invention comprises, in general, a base member 1 for supporting stationary contact 75 members 2 and 3, a housing 4 having an electromagnet 5 mounted therein, a switch arm 6 that is controlled by an operating handle 7, and a latching and tensioning mechanism 8 for moving them through a predetermined 80 cycle of operations.

An armature 12 for the electromagnet 5 is carried by a supporting member 13 that is, in turn, pivotally mounted on a shaft 14 that is supported by outwardly-projecting, spaced 85 flanges 15 formed on the housing 4. The shaft 14 supports also a pair of triggers 16 and 17, the details of which are shown in Figs. 7 and 8, 9 and 10, respectively. The triggers 16 and 17 are given a counter-clockwise bias 90 about the shaft 14 by coil springs 18 and 19, respectively.

Referring to Figs. 3, 7 and 8, the trigger 16 comprises a downwardly extending tail-piece 21, that projects thru an opening 22 in the 95 supporting member 13, and a main body portion 23 that terminates in a slot 24 having a notch 25 in one side.

Referring to Figs. 3, 9 and 10, the trigger 17 comprises a downwardly extending tail- 100

piece 26, that also projects thru the opening 22 in the supporting member 13, and a body portion 27 having a lug 28 formed on the upper edge thereof. The tail-piece 26 is 5 considerably narrower than the tail-piece 21 in order to permit movement of the former within the opening 22 independently of the latter.

Referring to Figs. 5 and 6, the switch arm 10 6 comprises a main body portion 29 having an upwardly extending perforated off-set arm 31, a portion 32 bent at right angles to the body portion, a forwardly projecting stop portion 33 and a lug 35 that is adapted to 15 co-operate with the notch 25 in the trigger 16. The switch arm 6 is supported on a shaft 36 that is secured between the flanges 15 above the shaft 14 in such position that its stop portion 33 may engage the housing 4, when 20 it is in its forward position. A bridging member 37 is riveted to the portion 32 and is provided with contact blades that co-operate with the stationary contact member 2 and 3 to complete the electrical connection therebetween. The operating handle 7 is also mounted 25 on the shaft 36.

Referring to Figs. 11 and 12, the handle 7 comprises a hand-hold 38, at one end, upper and lower oppositely projecting lugs 39 and 41, respectively, that are located approximately midway of its ends, and an upwardly projecting perforated off-set lug 42 located at the end opposite the hand-hold. A coil spring 43 connects the lug 42 of the handle 7 and the perforated arm 31 of the switch arm 6, thereby biasing the handle and the switch arm toward a predetermined angular relation about the shaft 36 upon which they are mounted. The lug 39 on the handle 7 is, in 40 turn, connected, by a coil spring 44, to a lug 45 on one of the flanges 15 of the housing 4. The spring 44 serves to bias the handle 7 and, in turn, the switch arm 6 in a clockwise direction toward the open position of the switch.

45 Assuming the switch to be in the open position shown in Fig. 1, and the lug 35 on the switch arm 6 to be in engagement with the notch 25 of the trigger 16, the handle 7 is turned about the shaft 36 until its lower 50 lug 41 slides over the lug 28 on the trigger 17. The trigger 17 is snapped into a forward position by the spring 19 and thereby locks the handle 7 in its "set" position, as shown in Fig. 3. The switch arm 6 is held in a retracted position against the tension of the spring 43 by the trigger 16.

The foregoing position of the switch may be retained indefinitely and, accordingly, a house-wife may set the switch in this position 60 upon leaving her home and adjust a clock (not shown) to further actuate the switch to close its contacts and thereby energize an electrical range at a predetermined hour.

When the electromagnet 5 is energized, as 65 by a clock, its armature 12 is drawn upward-

ly, thereby causing the supporting member 13 to bear against the tail-piece 21 and turn the trigger 16 until the lug 35 is disengaged from the notch 25, whereupon the spring 43 contracts and turns the switch arm 6 with a snap action to cause the blades of the bridging member 37 to engage the stationary contact members 2 and 3, as shown in Fig. 4. During the foregoing movement, no movement of the tail-piece 26 is effected because 70 avoided by reason of the difference in the widths of the tail-pieces 21 and 26.

After the switch has remained in its closed position for a predetermined interval of time, corresponding to that required for 80 cooking any desired food, the electromagnet 5 is again energized to turn the supporting member 13 to engage and actuate the tail-pieces 21 and 26. The actuation of the tail-piece 26 moves the lug 28 on the trigger 17 from beneath the lug 41 on the handle 7, whereupon the latter is snapped to its open position by the spring 44. In moving to its open position, the handle 7 engages the lower edge of the portion 32 of the switch arm 6 and thereby disengages the bridging member 37 from the stationary contact members 2 and 3. The switch is again in the position shown in Fig. 1, preparatory to a repetition of the foregoing cycle of operations.

It will thus be seen that I have provided a simple and effective switch for the operation of electrical heating appliances, particularly electrical ranges, which switch may be set in one position to thereafter automatically complete a desired cycle of operations through the use of a single electromagnet.

Although I have described a specific embodiment of my invention, it will be apparent to those skilled in the art that various changes, modifications, substitutions and omissions may be made therein without departing from the scope of my invention as set forth in the appended claims.

I claim as my invention:

1. In a switch mechanism, a base member, a stationary contact member and a housing mounted thereon, an electromagnet in said housing, a movable contact member supported on said housing and having an open and a closed position, an armature-supporting member mounted on the housing and having an opening therein, a plurality of triggers projecting through the opening in said armature-supporting member, an operating handle mounted on the housing and having a set and an open position, a spring for biasing the movable contact member toward its closed position, and a spring for biasing the operating handle toward its open position, whereby, upon moving the operating handle to its set position, the movable contact member is biased by its spring toward its closed position and is prevented from moving by one of said triggers, and the operating han-

dle is biased by its spring toward its open position and is prevented from moving by the other of said triggers, so that, upon energization of the electromagnet, one of the 5 triggers releases the movable contact member and, upon a subsequent energization of the electromagnet, the other trigger releases the operating handle to permit it to move to its open position and to actuate the movable 10 contact member to its open position.

2. In a switch mechanism, a base member, a stationary contact member and a housing mounted thereon, an electromagnet mounted in said housing, a movable contact member 15 and an operating handle mounted on the housing, and a plurality of tensioning and latching means whereby, upon movement of the operating handle to a predetermined position, the movable contact member is 20 biased toward the stationary contact member and prevented from moving by the latching means, and the operating handle is biased toward an open position and prevented from opening by the latching means, so that, upon 25 energization of the electromagnet, the latching means releases the movable contact member to permit it to engage the stationary contact member and, upon a subsequent energization of the electromagnet, the latching 30 means releases the operating handle to permit it to move to its open position, thereby moving the movable contact member out of engagement with the stationary contact member.

3. In a switch structure, a base member, a stationary contact member and a housing mounted thereon, an electromagnet mounted in the housing, a contact member pivotally mounted on the housing and having an open 40 and a closed position, an operating handle mounted on the housing and having a set and an open position, a plurality of triggers and tensioning means constituting a lost-motion connection between the operating handle and the pivotally mounted contact member, whereby, upon moving the operating handle to its set position, the switch is biased toward 45 its closed position and locked in its open position, and the operating handle is biased toward its open position and locked in its set position, so that, upon energization of the electromagnet, the pivotally mounted contact member is released to move to its closed position and, upon a subsequent energization of the electromagnet, the operating handle and the movable contact members are released 50 to move to their open positions.

4. In a switch structure, a base member, a stationary contact member and a housing mounted thereon, a contact member pivotally mounted on the housing and having an open and a closed position, an operating handle having an open and a set position, an electromagnet mounted within the housing, an armature supported by a bracket mounted on 60

the housing and having an opening, a plurality of triggers having ends projecting through said opening, a plurality of springs adapted to bias the triggers in one direction, a spring for biasing the operating handle toward its open position, and a spring for biasing the pivotally mounted contact member toward its closed position, with the operating handle in its set position, whereby, upon moving the operating handle toward its set 70 position, the pivotally mounted contact member is biased toward a closed position and is prevented from closing by one of the triggers, and the operating handle is biased toward an open position and is prevented from closing by another of the triggers, so that, upon energization of the electromagnet, the pivoted contact member is released to move to its closed position and, upon a subsequent energization of the electromagnet, the operating 75 handle is released to move to its open position and to actuate the pivoted contact member to its open position.

5. A switch mechanism comprising a base member, a stationary contact member, a movable contact member having an open and a closed position, an electromagnet, an operating handle having a set and an open position, a plurality of springs adapted to bias the movable contact member and the operating handle, a plurality of triggers adapted to control the operating handle and the movable contact member, whereby, upon energization of the electromagnet, the movable contact member is released to move to its closed 80 position and, upon the subsequent energization of the electromagnet, the operating handle and the movable contact member are released to move to their open positions.

6. In a snap switch, a stationary contact member, a movable contact member having an open and a closed position, an operating handle having a set and an open position and a lost-motion connection to the movable contact member, an electromagnet and the operating handle comprising a plurality of tensioning means, and a latching means for causing the operating handle to bias the movable contact member toward its closed position while it is locked in its open position, whereby, upon energization of the electromagnet the movable contact member is released to move to its closed position and, upon the subsequent energization of the electromagnet, the operating handle and the movable contact member are released to move to their open positions.

7. The combination in a switch having separable contact members, of biasing means adapted to close and to open the contact members, operating means for stressing the biasing means and a pair of latches one for holding the contact members in biased open position, the other for retaining the operating means in stressed position.

8. The combination in a switch having separable contact members, of two biasing means one of which is adapted to close and the other to open the contact members, operating means for stressing both of the biasing means and tripping means adapted to release one of the biasing means to close the contact members and to thereafter release the other biasing means to open the contact members. 70
10. The combination in a switch having separable contact members, of biasing means adapted to close and open the contact members, operating means for stressing the biasing means for a complete opening and closing operation and tripping means adapted to release the biasing means to close and to open the contact members in a predetermined sequence. 75
15. The combination in a circuit interrupter having a stationary and a movable contact member, of an operating member associated therewith, a biasing member connecting the operating member to the movable contact member, a biasing member connecting the operating member to the frame and a pair of latches associated with the movable contact member. 80
20. The combination in a circuit interrupter having separable contact members, of an operating member associated therewith, a biasing member connecting the operating member to the movable contact member, a biasing member connecting the operating member to the frame and a pair of latches associated with the movable contact member. 85
25. The combination in a circuit interrupter having separable contact members, of biasing means for moving the contact members to closed position, a biasing means for moving them to open position, operating means for stressing the biasing means simultaneously and means adapted to retain them in stressed position. 90
30. The combination in a circuit interrupter having separable contact members, of two biasing means one of which is employed to move the contact members to closed and the other to open position and operating means for stressing both of the biasing means. 95
35. The combination in a circuit interrupter having separable contact members, of a pair of biasing members for operating the contact members to closed and to open position, operating means for tensioning both of the biasing members, a latch associated with each of the biasing members adapted to retain them in tensioned position and an electromagnet adapted to release the latches in sequence. 100
40. The combination in a circuit interrupter having separable contact members, of a pair of biasing members for operating the contact members to closed and to open position, operating means for tensioning both of the biasing members, a latch associated with each of the biasing members adapted to retain them in tensioned position and an electromagnet adapted to release the latches in sequence. 105
45. The combination in a circuit interrupter having separable contact members, of a pair of biasing members for operating the contact members to closed and to open position, operating means for tensioning both of the biasing members, a latch associated with each of the biasing members adapted to retain them in tensioned position and an electromagnet actuating the latches in sequence adapted to close the contact members upon its first energization and to release the contact members on a subsequent energization. 110
50. In a switch of the above described type, in combination, a stationary contact member, a movable contact member, biasing means adapted to actuate the movable contact member to closed and to open position, operating means for tensioning the biasing means, a latch for retaining the operating means in tensioned position, a second latch for retaining the movable contact in open biased position and a solenoid for actuating the said latches. 115
55. In a switch of the above described type, in combination, a stationary contact member, a movable contact member, biasing means adapted to actuate the movable contact member to closed and to open position, operating means for tensioning the biasing means, a latch for retaining the operating means in tensioned position, a second latch for retaining the movable contact in open biased position and a single solenoid for actuating the said latches. 120
60. In testimony whereof, I have hereunto subscribed my name this 11th day of October, 1926. 125
- CHRISTIAN AALBORG. 130
